UNITED STATES PATENT OFFICE.

WILLIAM J. COOK, OF CHARLOTTE, NORTH CAROLINA.

AIR-VALVE FOR STEAM-RADIATORS.

1,337,045.

Specification of Letters Patent. Patented Apr. 13, 1920.

Application filed September 11, 1919. Serial No. 323,103.

To all whom it may concern:

Be it known that I, WILLIAM J. COOK, a citizen of the United States, residing at Charlotte, in the county of Mecklenburg 5 and State of North Carolina, have invented new and useful Improvements in Air-Valves for Steam-Radiators, of which the following is a specification.

This invention relates to improvements 10 in air valves for steam radiators and its object is to provide, a simply constructed valve organization wherein the valve element will be sensitive in its operation and will certainly and reliably prevent the escape 15 of steam and water of condensation, and wherein the parts are readily accessible for any desired or necessary purposes, but are devoid of any features of adjustment such as might impair the effective operation 20 of the valve.

An embodiment of the invention is illustrated in the accompanying drawing, wherein:—

Figure 1 is an elevation of a steam radiator equipped with an air valve in accordance 25 with the invention;

Fig. 2 is an elevation of the air valve;

Fig. 3 is a vertical central sectional view 30 of the air valve; the scale of this figure being exaggerated to promote clearness of illustration;

Fig. 4 is a horizontal sectional view on the line 4—4 of Fig. 3; and

Fig. 5 is a plan view of the valve.

Similar characters of reference designate 35 corresponding parts throughout the several views.

The casing of the air valve comprises a tubular upright body 1, an upper cap 2 40 and a lower cap 3. The caps 2 and 3 are threaded on the body 1 and the cap 3 has a central opening which aligns with the pipe 4 by which the valve is supported and also connected to the radiator. The pipe 2 is 45 provided with a series of perforations 5 which permit the normal escape of air from the radiator.

The casing incloses a vertically slidable 50 valve 6 which preferably has a cone-shaped body 7 and a flange 8 circumscribing said body at its open lower end. The valve 6 is guided in its movements by a pair of parallel vertical rods 9 which are arranged in diametrically opposite relation and extend between the caps 2 and 3. The rods 9 are preferably secured at their lower ends

to the cap 3 and their upper ends bear against the cap 2. The flange 8 is provided with openings through which said rods project; and thereby the valve 6 is guided 60 and steadied in its vertical movements.

Said valve has a free or floating action and is raised by steam pressure, the construction being such that in its uppermost position said valve cuts off the interior of 65 its casing from communication with the openings 5 and in any position below its uppermost position establishes communication between the interior of its casing and said openings. For this purpose the interior of the body 1 preferably has a suitable upward taper whereby when the valve is in its uppermost position, as shown by dotted lines A in Fig. 3, the peripheral edge of the flange 8 will have uniform contact 70 with the inner surface of the body 1, and when the valve is in any lower position, as shown by dotted lines B, an annular clearance 10 will be left between the peripheral edge of the flange 8 and the inner 75 face of the body 1. The clearance 10, as is obvious, provides for the normal escape of air from the tube 4 through the valve casing and thence through the openings 5; and it will be manifest that when the valve is in 80 its upper position with its edge in uniform contact with the inner face of the body 1, said clearance will be entirely eliminated and the interior of said body will be cut off from communication with the openings 5.

The valve normally assumes by gravity a position wherein the clearance 10 is effective, as described, to pass air. When the air has been vented from the radiator and 95 steam flows through the connection 4, the immediate effect is the movement of the valve, under the steam pressure, to its uppermost position, in which the valve prevents the escape of steam through the 100 openings 5.

The conical form of the valve has several advantages; first, it increases the effective area of the valve and, therefore, insures its sensitive resistance to pressure 105 variations; second, it insures that the pressure acts with strongest effect at the center of the valve and, hence, provides for the alinement of the valve in the casing and for its free movement along the guide rods 110 9; and third, it traps any water of condensation, preventing such water from being

blown through the openings 5 and insuring its return to the radiator through the connection 4.

Having fully described my invention, I claim:

1. An air valve for steam radiators comprising a vertical casing having a tubular connection at its lower end and having air escape openings at its upper end, a valve element freely movable in said casing and a pair of guide rods along which said valve element may slide, said valve element being subjected to air and steam pressure transmitted by said connection and in its uppermost position coöperating with said casing to cut off its communication with said openings.
2. An air valve for steam radiators comprising a vertical casing having a tubular connection at its lower end and having air escape openings at its upper end, said casing having its inner face upwardly tapering and a valve element freely movable in said casing, said valve element being subject to air and steam pressure transmitted by said connection and in any lower position having a clearance between its lower peripheral edge and said casing, while in its uppermost position its lower peripheral edge uniformly contacts with said casing.
3. An air valve for steam radiators comprising a vertical casing having a tubular connection at its lower end and having air escape openings at its upper end, said casing having its inner face upwardly tapering, a valve element freely movable in said casing, said valve element being subject to air and steam pressure transmitted by said connection and in any lower position having a clearance between its peripheral edge and said casing while in its uppermost position its peripheral edge uniformly contacts with said casing, and a pair of parallel guide rods extending throughout said casing and along which said valve element is slidable.
4. An air valve for steam radiators comprising a vertical casing having a tubular

connection at its lower end and having air escape openings at its upper end, a valve element freely movable in said casing and having a conical body open at its lower end, and a pair of guide rods along which said valve element may slide, said valve element being subject to air and steam pressure transmitted by said connection and in its uppermost position coöperating with said casing to cut off its communication with said openings.

5. An air valve for steam radiators comprising a vertical casing having a tubular connection at its lower end and having air escape openings at its upper end, said casing having its inner face upwardly tapering and a valve element freely movable in said casing and having a conical body open at its lower end, said valve element being subject to air and steam pressure transmitted by said connection and in any lower position having a clearance between its lower peripheral edge and said casing while in its uppermost position its lower peripheral edge uniformly contacts with said casing.

6. An air valve for steam radiators comprising a vertical casing having a tubular connection at its lower end and having air escape openings at its upper end, said casing having its inner face upwardly tapering, a valve element freely movable in said casing and having a conical body open at its lower end, said valve element being subject to air and steam pressure transmitted by said connection and in any lower position having a clearance between its peripheral edge and said casing while in its uppermost position its peripheral edge uniformly contacts with said casing, and a pair of parallel guide rods extending throughout said casing and along which said valve element is slidable.

In testimony whereof I have hereunto set my hand in presence of two subscribing witnesses.

WILLIAM J. COOK.
